Primary Examiner — Manpreet S. Matharu*Assistant Examiner* — J. Thorn, Sr.(74) *Attorney, Agent, or Firm* — Hulsey P.C.(57) **CLAIM**

The ornamental design for a hooded short cropped coat, as shown and described.

DESCRIPTION

FIG. 1 is an isometric view of a hooded water-resistant hunting coat with a weather mask, a suite of pockets, a kill switch D-ring, and a drop-down seat attachment which can be stowed away in the inner torso of said jacket, showing my new design.

FIG. 2 is a front perspective view of hooded water-resistant hunting coat

FIG. 3 is a back perspective view thereof.

FIG. 4 is a top perspective view thereof.

FIG. 5 is a bottom perspective view thereof.

FIG. 6 is a left elevation view thereof; and,
FIG. 7 is a right elevation view thereof.

The broken lines shown in the drawings represent stitching in the fabric.
